UNITED STATES PATENT OFFICE.

WILLIAM JOHN BRETT, OF COVENTRY, ENGLAND, ASSIGNOR TO FRANK JELLINGS, OF LEEDS, ENGLAND.

FLUSHING-VALVE.

1,102,469.

Specification of Letters Patent.

Patented July 7, 1914.

Application filed March 18, 1913. Serial No. 755,263.

To all whom it may concern:

Be it known that I, WILLIAM JOHN BRETT, residing at 1 Albany road, Coventry, in the county of Warwick, England, 5 have invented a new and useful Improvement in Flushing-Valves, of which the following is a specification.

This invention has reference to the valves of flushing cisterns, water waste preventers 10 and the like and more particularly to the type of valve which is made in two parts, one of which is mounted loosely on the valve rod and is adapted to close the valve orifice while the other part is attached to 15 the valve rod and normally takes a seating upon the loose part for the purpose of preventing leakage taking place between the latter and the valve rod when the valve as a whole is closed. While this type of valve 20 when completely closed is sufficiently water-tight it is conceivable that owing to the necessary loose fit between the valve rod and the loose part of the valve leakage to a more or less extent is liable to take place 25 where for any reason the part of the valve which is fixed to and moves with the valve rod has an imperfect seating on the loose part or where the valve is left or held partly open, *i. e.* with the fixed part of the valve 30 out of contact with the loose part.

The object of this invention is to provide against the aforesaid contingencies and without in any way affecting the function of the valve as a whole to design the valve 35 in such a manner that the possibility of leakage under such circumstances as above referred to is completely avoided.

In order that my invention may be clearly understood and readily carried into 40 effect reference is made in describing the same to the accompanying drawing which represents in central vertical section a flushing cistern embodying the present invention.

Referring to the drawing, 2 represents 45 the hollow body of the cistern and 3 the cover which is bolted to the flanged upper edge of the cistern so as to make the latter completely air-tight and has formed with it a central depending tubular chamber 4. 50 This chamber is in open communication at the top with the water supply main and is provided at its lower end which extends almost to the bottom of the cistern, with lateral ports 5 and an internal brass bush 55 6 in which works the admission and cut-off

valve 7 for controlling said ports. The valve may conveniently be formed integral with the upper part 8 of the two part delivery valve the lower part 9 of which is mounted loosely on the valve rod 10 and is 60 not raised thereby to open the delivery orifice until after the admission valve has closed the ports 5 and thereby cut off the cistern from the supply main.

In order to render the two part delivery valve completely water-tight especially when left partly open, *i. e.* with the upper part 8 of the valve raised from its seating on the lower part 9, the said lower part is provided with a sleeve extension 11 65 which has a sliding fit on the valve rod and passes through the delivery valve orifice, its free end entering and working within an enlarged part 12 of the bore in the stuffing box 13 through which the valve rod 70 passes. The said sleeve extension 11 may be made either in one piece with the loose valve part 9 or separately and secured thereto by a screw thread and nut 14 as shown or in any other suitable manner. 80

In the above described construction the body of the loose valve part is preferably recessed at 15 to accommodate the stop 16 on the valve rod whereby the said loose part of the valve is raised from its seat subsequently, to the lifting of the fixed valve part 8 and the simultaneous closing of the ports 5 by the admission valve 7. The recessed face of the loose valve part is closed 85 by a plate 17 which forms the necessary abutment against which the stop 16 makes contact during the opening movement of the valve rod.

18, 19 are valve seatings formed of leather or any other suitable material and which are held in position respectively by the sleeves 20 and 21 as shown. 95

The valve 7 and two part delivery valve 8 and 9, and valve rod 10 are raised by the lever 21 connected by the link 22 to the projection 23 on the undersurface of the delivery portion 24 of the cistern. 100

The action of the apparatus is as follows:—The water from the main source of supply enters the interior of the tubular chamber 4 and passes into the cistern 2 through the lateral ports 5 until the cistern is filled to the required height. When it is desired to use the water in the cistern for flushing purposes the free end of lever 21 105 110

is depressed and by the connection of the lever with valve rod 10 the latter is raised and valve 7 closes the ports 5 before the lower part 9 of the two part delivery valve is raised. The first movement of the valve rod 10 will raise the upper portion of the two part delivery valve until the stop 16 comes in contact with the plate 17. When this contact takes place the ports 5 will have been closed. The continued upward movement of the valve rod 10 raises the lower part 9 of the two part delivery valve and lifts the valve clear of the valve seating 25, thus permitting the water in the cistern to pass into and escape through the delivery portion 24. On the valves being returned to the normal position shown in the drawing the ports 5 will be again opened for the admission of water through tubular chamber 4 into the interior of the cistern 2.

What I claim is:—

1. In a flushing cistern having a removable cover and a discharge opening in its base, the combination therewith of a water inlet tube pendent from said cover and provided with a valve seat and outlet ports at its lower end, a delivery valve formed in two independently movable parts, the lower of said parts controlling the outflow through said discharge opening, having a recess in its upper face and a perforation through said part continuous with said recess, a disk for closing said recess, a spindle slidable to a limited extent through said perforation rigidly secured to said upper part for opening the same and having a projection within the recess to engage said disk to raise the lower part of the valve, and an inlet valve continuous with said upper part of the dis-

charge valve adapted to close the outlet ports in the inlet valve pipe before the discharge is opened when the spindle is raised, and open said ports after the discharge is closed when the spindle is lowered.

2. The combination of a flushing cistern provided with a removable cover and having an opening in its base, a tubular chamber pendent from said cover and having a bushing at its lower end and provided with lateral ports, a delivery portion fixed to the base of said cistern and having an outlet passage communicating with the interior of the cistern, a gland fixed to the base of the delivery outlet, a valve seating on the top of the said outlet, a delivery valve made in two portions provided with recesses, a tubular sleeve extension piece fixed on its upper end to the lower portion of the delivery valve and its lower end being arranged to slide in the said gland, an admission and cut-off valve fixed to the upper part of the delivery valve and working in the bushing of the tubular chamber, a valve spindle fixed at its upper end to the upper portion of the delivery valve and arranged to pass through the extension sleeve and gland of the delivery outlet, a stop fixed on the spindle arranged to work in the recess of the lower portion of the delivery valve, a plate fixed to the top of the said lower portion and arranged to cover the recess therein and means for operating the said spindle and valves as described.
